EXPANSIBLE ANCHOR

Charles E. Handel, Winterset, Iowa, assignor to
Wej-Lock Manufacturing Company, Winter-
set, Iowa, a corporation of Iowa

Application January 6, 1932, Serial No. 585,005

3 Claims. (Cl. 189—92)

This invention relates to improvement in expansion anchors of that type having a spreader plate, an anchor rod and a movable member on the rod for supporting a series of anchor blades, in which the blades are normally supported in a folded position substantially parallel with the rod, so that the folded assembly may be placed in a comparatively small hole, after which the blades are spread to an open position by moving the movable member toward the spreader plate.

The object of my invention is to provide in an anchor of the type above described, improved means whereby a number of anchoring blades may be considerably increased, and whereby the effective combined anchorage surface of the blades may be considerably increased over devices heretofore used.

A further object is to provide in an anchor of the type above described improved means for locking the blades against folding after they have been spread, said locking means being so arranged that the blades will be locked at a comparatively large number of expanded positions to reduce the initial pull or give of the anchor to a minimum as tension is applied to the anchor rod.

A further object is to provide in an expansion anchor of the type above described, in which is employed a sliding head, improved means for pivotally connecting the blades to said head.

A further object is to provide an expansion anchor of simple, durable and inexpensive construction which may be easily and quickly assembled, and when so assembled is of rigid construction and positive in its action.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of my improved anchor with the anchor blades in their folded position, a portion of the anchor being shown in section.

Figure 2 is an enlarged, detail, sectional view taken on the line 2—2 of Figure 1.

Figure 3 is a plan view of the anchor in its expanded position, the anchor rod being removed.

Figure 4 shows the manner in which my improved anchor is supported in the ground before the opening through which the anchor is inserted has been filled.

Figure 5 is a detail sectional view of a modified form of my anchor.

Figure 6 is a plan view of one of the anchor blades used in the modified form.

Referring to the accompanying drawing I have used the reference numeral 10 to indicate a spreader plate, preferably circular in formation, having its top surface formed spherical. Said spherical portion comprises a series of annular steps 11 concentrically arranged with the center of the plate 10. Said steps may be machined in the plate or cast integral therewith.

Projecting upwardly from the center of the plate 10 is an anchor rod 12, preferably having its lower end screw threaded and screwed into a threaded opening 13 in the plate 10. Slidably mounted on the rod 12 is a head member 14 comprising a circular plate 15 having a series of lugs 16 extending downwardly from its under surface and near its periphery.

An annular pivot bar 17 is fixed to the lower ends of the outer edges of said lugs 16, so that a series of openings 18 are formed between said lugs, each of said openings being designed to receive a hinge portion 19 of an anchor plate 20, said hinge member being in the form of an upwardly and outwardly extending hook portion 25 cast integral with the blade 20.

Each of the blades 20 has an inclined portion 21 at one edge so arranged that when the blades are in a substantially vertical position with their lower ends resting against the periphery of the disk 19, then the portions 21 will underlap the adjacent edges of the blades 20, in the manner illustrated in Figures 1 and 2.

Each of the blades 20 has an outwardly extending lug 23 to prevent the binding wire 24 from slipping upwardly. Said wire supports the blades in the folded position, as illustrated in Figures 1 and 2. It will be seen by reference to Figure 1, that the folded blades 20 and the members 10 and 15 provide a hollow body having substantially the shape of a truncated prism.

The inner edge of each of the portions 21 is provided with a series of teeth 25 designed to engage the edges of the steps 11 of the plate 10 when the blades 20 are in their expanded positions as shown in Figures 3 and 4, and thereby provide means for locking the blades against folding as outward tension is applied to the rod 12.

In applying the anchor, a hole 26 is first formed in the ground surface, said hole being of a diameter slightly greater than the diameter of the base of the anchor body when in a folded position. The anchor is then placed in the bottom of the hole in the position shown by dotted

lines in Figure 4, with the plate 10 resting firmly on the bottom of said hole.

The head 15 is then driven downwardly by means of a suitable tamper, which will cause the lower edges of the plates 20 to be moved downwardly past the periphery of the plate 10 and to be moved to the expanded position shown in Figure 4, the folded anchor being in the hole with the wire 24 intact, said wire being broken by the expanding strain of the blades 20.

The wire 24 provides means for binding the blades together until the anchor is properly placed in the bottom of the hole. The annular pivot member 17 is of less diameter than the expanding plate 10, so that as the head 15 is moved toward the said plate 10, the lower ends of the blades 20 will be swung to position in a plane substantially perpendicular to the rod 12, in which case the outer edge of the plate 10 serves as a fulcrum for the blades as they are moved into their expanded position.

The teeth 25 and the steps 11 provide means whereby the blades will be locked against folding movement as the rod 12 is pulled outwardly, even if the said blades are not moved to their maximum expanded positions. By providing a comparatively large number of teeth 25, the amount of initial upward movement of the plate 10 as strain is applied to the rod 12 will thereby be decreased to a minimum.

By forming the upper surface of the plate 10 somewhat spherical, it will be seen that the edges of some of the steps 11 will engage one or more of the teeth of the corresponding blade, whether or not the blades have been moved to fully expanded position, whereby the blades will be locked even if said blades assume a number of angular positions relative to the plate 10, thereby providing for positively locking the blades even if they are not moved to their maximum expanded positions.

Figures 5 and 6 illustrate a modified form of locking means in which each of the blades 20 is provided with a slot 27 arranged substantially radially with the rod 12. Outwardly extending lugs 28 are supported preferably near the outer end of each of said slots, said lugs being designed to pivotally receive a pawl 29, said pawls being secured in position by a cotter pin 30. Some of the pawls 29 are shorter than others. A flat disk 31 is then substituted for the plate 10, said disk being secured to the lower end of the rod 12.

By this arrangement it will be seen that if the blades 20 are moved downwardly and outwardly past the periphery of the disk 31, the free ends of the pawls 29 will drop back of the periphery of said disk and thereby provide a lock for pre-

venting inward and upward movement of the blades 20.

By providing pawls of different lengths, means is provided whereby the blades may be locked at various angles relative to the disk 31. The outer end of each of the pawls 29 is designed to rest against the outer end of the slot 27 to relieve the cotter pins 30 of any strain as it is applied to said pawls.

I claim as my invention:

1. An expandible anchor comprising a circular spreader plate having its upper surface formed substantially spherical and provided with a series of annular and concentrically arranged steps, an anchor rod through said plate, a head member slidably mounted on said rod, a series of anchor blades having their upper ends pivoted to said head and their lower ends resting against the periphery of said plate when folded, one edge of one blade overlapping the adjacent edge of an adjacent blade to form a hollow body having the form of a truncated prism, the inner surface of the underlapping edges of said blades being provided with teeth to coact with said steps when expanded to lock the blades against folding when strain is applied to said rod.

2. An expansion anchor comprising a spreader plate having its upper surface consisting of a series of closely arranged steps extending downwardly from its central portion, an anchor rod connected to said plate, a head member slidably mounted longitudinally of said rod, a series of anchor blades having their upper ends pivotally connected to said head and their lower ends resting against the edge of said plate when folded, one edge of each blade continuously overlapping the adjacent blade to form a hollow body, the inner surface of each blade having a series of closely arranged and inwardly projecting teeth to coact with said steps when the blades are in an expanded position to lock the blades against folding when strain is applied to said rod.

3. An expandible anchor comprising a circular spreader plate having its upper surface formed substantially spherical and provided with a series of annular and concentrically arranged steps, an anchor rod through said plate, a head member slidably mounted on said rod, a series of anchor blades having their upper ends pivoted to said head and their lower ends resting against the periphery of said plate when folded, the inner surfaces of said blades being provided with closely arranged teeth to coact with said steps when moved to any one of a number of expanded positions to lock the blades against folding when strain is applied to said rod.

CHARLES E. HANDEL.
